WELL PUMP

Kork Kelley, Wichita Falls, Tex.

Application June 3, 1946, Serial No. 673,981

3 Claims. (Cl. 103—179)

1

This invention relates to valve controlled pumps, and has particular reference to pumps adaptable to the displacement of oils and gases.

In conventional pump construction, little or no provision has been made for displacement or disposition of gases entrapped between the suction and discharge valves and in the process of pumping oil from a well most of the oil and water pumps in universal use contain a clearance space between the traveling and standing valves of approximately twenty percent of the entire volumetric pump displacement.

As the compressibility of oil and water is negligible, the conventional type pump performs satisfactorily when only such matter is encountered. However, when gas is encountered and enters the pump chamber between the traveling and standing valves, the efficiency of the pump is greatly impaired and in many instances totally inadequate. These gases remain in the clearance chamber, and owing to their high compressibility, cause the pump to become "gas locked."

It is the principal object of this invention to reduce the clearance chamber between the suction and intake valves of a pump to a minimum volume, and in so doing eliminate the possibility of failure by a gas-lock, since it is generally known that various liquids assume a fluid or a gaseous state when subjected to varying degrees of temperature and compression.

Another object of this invention is to provide a pump capable of producing an uninterrupted flow of fluid or gaseous matter.

Another object of the invention is to provide an efficient pump having a clearance chamber with a minimum volumetric capacity.

Still another object of the invention is to provide a pump containing a standing valve adaptable to minute adjustment.

With the foregoing objects as paramount, this invention has further reference to certain features of accomplishment and arrangement of essential parts, which will become increasingly apparent as the description proceeds, taken in connection with the accompanying drawings, wherein:

Figure 1 is a fragmentary elevational view of the invention in vertical section showing the inner construction details of the traveling valve in its relationship with the enclosing pump barrel, the traveling valve being shown at the end of its downward stroke.

Figure 2 is a fragmentary elevational view

2

of the barrel, the standing valve and the traveling valve illustrated in larger detail.

Figure 3 is an elevational view of a portion of the traveling valve, shown partially in section.

Figure 4 is an elevational view of the lower extremity of the pump barrel.

Figure 5 is a transverse sectional view taken on line 5—5 in Figure 2, and

10. Figure 6 is a modified form of the standing valve of the invention showing the surrounding parts in vertical section.

A large percentage of wells which produce petroleum will continue to produce large amounts of gas after cessation of natural flow. This gas originates from two sources, being either the free or solution gas. The temperature and pressure changes which these gases undergo are seldom compensated for in conventional pump design and since the gas is compressible, expansion takes place after compression if space is provided therefor. Conventional oil well pumps are only single acting, that is, they are designed to intake fluid on the upstroke

15 and transfer the fluid above the upper valve on the downstroke and in practically all pump designs there is a clearance space between the suction and discharge valves when the plunger completes its discharge stroke, which space amounts to 20% or more by volume of the total volumetric displacement of the pump.

All of the gas remaining in the clearance space between the valves is compressed to a pressure equal to the discharge pressure. If this gas or gaseous fluid under pressure is of such volume that it will occupy the space made by the plunger on the next intake stroke, the pump will intake no product and will become "gas locked" or "air bound" as this condition is commonly called.

20. The clearance space above referred to is due to the design of the upper and lower valves, cages and associated parts of a pump and it is the purpose of the present invention to eliminate a greater part of this space in order that the volume of gas capable of being entrapped therein will be reduced to the very minimum, thereby to obviate the troublesome gas and air locks referred to.

25. With the foregoing in view, further reference is made to the drawing wherein numeral 10 denotes a pump barrel having threaded thereon a suction valve casing 11, to which is joined a bottom extension 12. Within the pump barrel 10 reciprocates a traveling valve 13, the latter be-

ing entirely conventional but further reference thereto will be made presently.

The present invention which must include relationship with conventional parts described and to be described, consists of a valve guide 14 mounted in the casing 11 which abuts an annular shoulder *a* interiorly of the casing 11. This shoulder also serves as a seat for a spherical valve drop 15, having a stem 16 which reciprocates in the guide 14. The guide 14 has passages 16a longitudinally therethrough for upward passage of fluid. To limit the degree of displacement of the valve drop 15 in relation to its seat *a*, a collar 17 is mounted on the stem 16 below the guide 14, said sleeve being obviously capable of adjustment longitudinally of the stem to vary the degree of displacement of the valve drop.

The traveling valve is provided with a conventional fluid tube 18 which communicates with a fluid displacement chamber 18a immediately above the ball valve 19 operating in relation to a seat 20 in the lower end of the traveling valve 13. A companion ball drop 21 is in control of the upper end of the fluid displacement tube 18 while conventional cups 22 surround the tube intermediate its ends.

As stated previously, the importance of the invention resides in the relative spacing of the lower valve 19 and the standing valve 15. Therefore, the extension or standing valve casing 11 is reduced in length to allow the lower end of the traveling valve to approach contiguity with the spherical standing valve 15, thereby reducing to a negligible degree the capacity of the clearance space or chamber 23 when the traveling valve is at the limit of its downstroke.

It is obvious that since the valve drops 19 and 15 are caused to be brought into close relative proximity, there is little product present in the chamber 23, thus reducing to a negligible degree the likelihood of a gas or air lock.

In Figure 6 is shown a slight modification in the form of the standing valve 15 in that the latter, instead of being of spherical shape, it is sub-hemispherical but has the depending guide or stem 16 and retaining collar 17, not unlike that of the spheroidal valve drop 15. However, by so constructing the valve drop, the clearance between the valve drops 15 and 19 is reduced even

more than is possible through the arrangement earlier described, i. e., with the spheroidal valve drop shown in Figures 1 and 2.

Manifestly, the construction as shown and described is capable of some modification and such modification as may be construed to fall within the scope and meaning of the appended claims is also considered to be within the spirit and intent of the invention.

What is claimed is:

1. A pump for volatile liquids having a working barrel and a hollow plunger, a discharge valve in said plunger, said plunger having a relatively thin lower end wall, a seat for said discharge valve in the lower end wall of said plunger, said end wall having a recessed bottom, a tubular extension on said working barrel defining a suction valve chamber, a reciprocable suction valve occupying substantially the entire volume of said chamber at the limit of the down-stroke of the plunger, the upper portion of said suction valve being disposed in the recess at the limit of the down-stroke of said plunger, said discharge valve being effective, on the down-stroke of said plunger, to reduce the volume of said gaseous product between said valves and to increase the fluid displacement of said pump by descending on its seat into contiguity with the upper portion of said suction valve, and means for limiting the displacement of said suction valve.

2. A pump as set forth in claim 1, in which said suction valve has a stem and an attendant guide and seat.

3. A pump as set forth in claim 1, in which said valve chambers are separated only by the thickness of said discharge valve seat.
